INVENTOR.
Knut B. Brynildson,

BY
Geo. P. Kimmel.
ATTORNEY.

UNITED STATES PATENT OFFICE.

KNUT B. BRYNILDSON, OF NEW RICHLAND, MINNESOTA.

ILLUMINATED LICENSE-PLATE HOLDER.

Application filed October 18, 1923. Serial No. 669,330.

To all whom it may concern:

Be it known that I, KNUT B. BRYNILDSON, a citizen of the United States, residing at New Richland, in the county of Waseca and State of Minnesota, have invented certain new and useful Improvements in Illuminated License-Plate Holders, of which the following is a specification.

This invention relates to illuminated license plate holders for auto driven vehicles, and has for one of its objects to improve the construction and increase the efficiency and utility of devices of this character.

Another object of the invention is to provide a device of this character having improved means for supporting an electric light bulb therein.

With these and other objects in view the invention consists in certain novel features of construction as hereinafter shown and described and then specifically pointed out in the claims, and in the drawings illustrative of the preferred embodiment of the invention—

25 Figure 1 is a front elevation, and

Figure 2 is a bottom plan view, of the improved device.

Figure 3 is a longitudinal section on the line 3—3 of Fig. 1.

30 Figure 4 is a transverse section on the line 4—4 of Fig. 3, looking in the direction of the arrow.

Figure 5 is a transverse section on the line 5—5 of Fig. 3, looking in the direction of the arrow.

35 Figure 6 is a detailed enlarged perspective view of a modified form of the attaching bracket.

The improved device comprises an oblong sheet metal shell or casing formed with rear 40 10, top 11, ends 12 and 13 and bottom 14, and a partial front 15, leaving the remainder of the front of the casing open.

Bearing over the open portion of the front 45 45 of the casing is a closure plate 16 with one end extending beneath the overhanging inner edge 17 of the partial front portion 15, as shown in 3. The closure member 16 is formed with a bead 18 around three sides 50 50 which bears over the adjacent edges of the casing, and is attached to the body of the casing by clamp bolts 19.

Formed on the forward edge of the top 11 is an overhanging rib or shield 36 and

operating as a water shed to protect the 55 members 16 from the elements.

The closure member 16 is pierced by apertures outlining the license number, and other required data, and bearing against the closure member is a transparent sheet 20, preferably of celluloid. The clamp bolts 19 pass through the transparent sheet 20.

The back 10 and the end 12 of the casing are lined with a reflecting element 21 of any suitable material.

Preferably located between the reflector element 21 and the back 10 of the casing is a packing of yieldable material such as soft card-board.

Inserted in the partial closure portion 15 70 is an annular frame 22 which supports a lens member 23 of colored glass, red when the device is located at the rear, or white when located at the front of the vehicle.

Formed in the bottom member 14 of the 75 casing beneath the portion 15 is an opening 24, and movably supported upon the bottom 14 is a slide 25 to partly cover the opening, the slide having a recess 26 which registers with a part of the opening 24 when the 80 slide is in its inner position, as shown in Fig. 2.

The slide 25 is formed with a slot 27 through which a headed pin 28 extends and thence into the body of the casing, by which 85 means the slide is movably coupled to the casing.

Extending through the opening 24 of the casing and the recess 26 of the slide is a two ended socket 29 for an electric light bulb 90 30, the outer portion of the socket being located externally of the casing in position to receive the conductor wires indicated at 31.

The socket 29 is secured to the casing by a small bracket 32 and clamp screw 33.

95 The casing is adapted to be coupled to any suitable part of the frame work of a vehicle, for instance by slotted clip members as shown at 34, by the form of clip shown in Fig. 6, or any other suitable form, depending on the structure of the vehicle to which the device is to be attached.

The bulb 30 being located within the casing at one end the light rays are projected against the reflector element 21 and thence 100 through the openings in the closure 16 which indicate the license number and other required matter, and illuminates the data and

renders it visible at night, and at the same time portions of the light rays illuminate the lens member 23. Thus one bulb only is required.

5 By arranging the socket 30 double ended, the plug 35 for the lamp socket can be detached or inserted from outside of the casing and independently of the bulb, or the bulb inserted or removed independently of
10 the plug.

The improved device is simple in construction, can be made of any size or proportion, or of any suitable material.

The preferred embodiment of the invention is disclosed in the drawings and set forth in the specification, but it will be understood that modifications within the scope of the claimed invention may be made in the construction without departing from the
20 principle of the invention or sacrificing any of its advantages.

Having thus described the invention, what is claimed as new is:—

1. In a device of the class described, a casing having internal reflecting elements and a

stationary closure extending over a portion of the front, a lens element in the stationary closure portion, a source of light within the casing rearwardly of the lens element, a removable closure for the remainder of the casing with one end extending beneath the inner edge of the partial closure, and an outstanding bead on the removable closure and bearing over the adjacent edges of the casing, said removable closure portion having transparent indicating data, and means for uniting the detachable closure portion to the casing. 35

2. In a device of the class described, an enclosed casing including top and bottom 40 portion, a closure member for the front of the casing and having beads bearing over the forward edges of the casing, means for coupling the closure to the casing and an extension on the top portion bearing over 45 the upper portion of the front and forming a shield to the movable closure.

In testimony whereof, I affix my signature hereto.

KNUT B. BRYNILDSON.
